ATOMIZER CONSTRUCTION

James R. Grosholz, Wayne, Pa., assignor to Air-Shields, Inc., Hatboro, Pa., a corporation of Delaware

Application December 1, 1954, Serial No. 472,329

6 Claims. (Cl. 299—142)

This invention relates to improvements in atomizing equipment and is particularly concerned with apparatus in which the atomizer unit is removable.

Atomizers which are used for breaking up liquids into finely divided particles and mixing them with air or other gases usually incorporate small passages which must be kept clear, as even partial clogging interferes with proper functioning. It is therefore desirable to provide means for inspecting and cleaning the small passages in order to maintain the atomizer in good operating condition. It is a particular object of the present invention to provide an atomizer construction which may be more quickly and easily mounted or dismounted to permit cleaning or replacing.

In order to prevent corrosive action in the small passages through the atomizer it is desirable to make the head portion of glass or other corrosion resistance material. It is an object of the present invention to provide a simple mounting structure for the atomizer head on the body and at the same time to provide protective structure to prevent damage to the fragile head parts.

A specific object of the invention is to provide an atomizer construction which permits it to be pushed into position in a cylindrical opening and to be retained in position by frictional restraint without the need for threads or other complicated fastening means.

How the foregoing and other objects and advantages are attained will be clear from the following description of the drawing in which—

Figure 1 shows a view partly in section of a humidifying device incorporating an atomizer constructed in accordance with the present invention.

Figure 2 is a side elevational view of the atomizer shown to an enlarged scale.

Figure 3 is a front elevational view of the atomizer device.

Figure 4 is a plan view of the atomizer.

The humidifier device shown in Figure 1 incorporates a body 10 to which a delivery duct 11 and a return circulation duct 12 are attached. The upper ends of these ducts are connected to the supporting wall 13 by means of clips 14 which engage the edge of suitable openings 15 in the wall 13. A reservoir 16 is attached to the lower end of the body 10 by means of the threaded cap 17. Flexible tube 18 delivers air or other gas for the operation of the humidifier through channel 19 in the body 10. The general construction of the humidifier device forms no part of the present invention per se since it is shown and claimed in the co-pending application of Samuel Y. Gibbon, Serial No. 350,452, filed April 22, 1953, now Patent No. 2,778,617, the present disclosure being by way of example of suitable equipment with which the improved atomizer of the present invention may be used.

In the body 10 a cylindrical opening 20 supports the atomizer unit 21. Channel 19 opens through the wall of cylindrical opening 20. Atomizer unit 21 incorporates a cylindrical portion 22 having a diameter and length to fit cylindrical opening 20. A groove 23 extends annular-

2

ly around the cylindrical portion 22 at a position in alignment with the end of channel 19. On each side of groove 23 a sealing ring 24 is mounted in a groove in the cylindrical portion 22 of the atomizer body. Below the opening 20 an enlarged portion 25 of the atomizer body produces a locating shoulder which assures that the groove 23 is properly positioned with respect to channel 19. This enlarged portion 25 also provides a convenient means for gripping the atomizer when it is being mounted or dismounted.

The atomizer head 26 is preferably made of glass or some other non-corrosive material and includes a nozzle 27 for delivering the gas supplied through tube 18. The liquid is delivered at the atomizer head through curved tube member 28, across the end of which the high velocity flow from nozzle 27 passes to create the suction for lifting the liquid. Two small nipples 29 and 30 are attached to the upper end of cylindrical portion 22. The head 26 is attached to these nipples, the nozzle 27 being attached to nipple 29 by means of flexible tubing 31 and tube 28 being attached to the nipple 30 by a similar tube 31a.

As will be seen more clearly in Figure 2 the opening in nozzle 27 connects up with channel 32 which extends from nipple 29 through the cylindrical portion 22 where it opens into the groove 23 at 33. The tube 28 also has a connecting channel 34 through nipple 30 which extends completely through the body of the atomizer as indicated. The channel 34 also passes through nipple 35 located at the bottom end of the enlarged portion 25 of the unit. Nipple 35 supports the flexible tube 36 which extends into the reservoir to supply the atomizer with the liquid. A screen 37 is used at the entry of tube 36 to remove particles of dirt before they reach the atomizer.

At the upper end of the atomizer unit the body portion 39 is formed generally cylindrical in shape having a diameter small enough to pass through the opening 20 in which the unit is mounted. By forming a slot in body portion 39 two legs or prongs 39a and 39b are formed, one on each side of the atomizer head. By this construction the delicate head unit 26 is protected from damage during the operation of inserting or removing the atomizer. The body of the atomizer is preferably molded from a plastic material which is impervious to water or other liquids which might be used.

From the foregoing it will be seen that I have provided an improved atomizer construction which may be quickly slipped into or out of operating position. The use of a cylindrical portion permits the unit to be mounted in a cylindrical aperture and to be adequately sealed by means of O-ring seals. These seals also provide the frictional characteristics for holding the atomizer in position. The use of a demountable head unit permits easy removal of this portion of the atomizer for cleaning. By means of the pronged extension of the atomizer body, an atomizer of rugged construction is produced which is not readily damaged during storage or when being mounted into operating position. With this construction the atomizer may be removed for cleaning or replacement in a matter of seconds, thereby greatly increasing the serviceability and utility of the equipment in which the atomizer is used.

I claim:

1. A delivery unit for an atomizer device, said unit having a body with a smooth cylindrical portion, a supporting structure for holding said delivery unit, said structure having a cylindrical opening of slightly larger diameter than said cylindrical body portion, a pair of spaced annular seals mounted on said cylindrical body portion and projecting slightly therefrom, said seals being resilient and having a diameter to firmly engage the wall

of the cylindrical opening to support said unit in position when inserted therein, said body having a channel with an opening in the wall of the cylindrical portion between said seals, said supporting structure also having a delivery channel therein with an outlet in the wall of the cylindrical opening, an atomizer head at one end of said body to which said delivery channel connects, said body also incorporating another channels extending from said head longitudinally therethrough for delivering fluid to said atomizer head, a fluid delivery tube attached to the end of said body opposite said head, said tube being removable as part of said delivery unit.

2. A delivery unit for an atomizer, a mounting block having a cylindrical opening, said unit having a body with a cylindrical portion to fit inside said opening, an atomizer head located at one end of said cylindrical body portion, said head being proportioned to pass through said cylindrical opening, said body having a channel extending from said head to an opening in the wall of said cylindrical portion, a pair of annular seals on said cylindrical body portion, one on each side of the wall opening, a second channel extending from said head longitudinally through said unit to a point beyond said annular seals, one of said channels providing for the delivery of liquid to said atomizer head, and the other of said channels providing for delivery of gas to said atomizer head, said body incorporating locating means to determine its longitudinal position when mounted in said mounting block, said seals being resilient and proportioned to contact the inner surface of the opening in said block to retain said unit in position.

3. A delivery unit for an atomizer having a body with a cylindrical portion adapted to be mounted in a cylindrical opening, an extended body portion located beyond said cylindrical portion, said extended body portion having a dimension smaller than the diameter of said cylindrical body portion, said extending portion being slotted to form two prongs, an atomizer head device supported between and protected by said prongs, two channels extending from said head device, said cylindrical portion having an opening in its wall, an annular seal on each side of said opening, one of said channels ending at the opening, the other of said channels extending to a point beyond said annular seals, said seals, being resilient and proportioned to engage the surface of the cylindrical opening for retaining said unit in operating position.

4. An atomizer construction according to claim 3 in which a pair of nipples are located at the bottom of the slot, said head being supported on said nipples.

5. Atomizing equipment including a readily removable delivery unit, said unit incorporating a cylindrical body, an atomizer head supported on said body, said body having two channels therein connected to said head for the delivery of liquid and gas thereto, said atomizing equipment incorporating a supporting block with a cylindrical cavity proportioned to receive said body, said body having an opening in its cylindrical wall at which one of said channels terminates, a pair of sealing rings one mounted on each side of said opening, said rings being proportioned to react between said body and the walls of the cavity to produce support for said delivery unit, and a channel in said supporting block leading to said cylindrical cavity at a point between said sealing rings when said body is mounted in position.

6. A delivery unit for an atomizer device, said unit having a body with a smooth cylindrical portion, a pair of spaced annular seals mounted on said cylindrical portion and projecting slightly therefrom, said seals being resilient and having a diameter to firmly engage the wall of a cylindrical opening to support said unit in position when inserted therein, said body having a channel with an opening in the wall of the cylindrical portion between said seals, an atomizer head at one end of said body to which said channel connects, said body also incorporating another channel extending from said head longitudinally therethrough for delivering fluid to said atomizer head, said body having an enlarged portion at the end thereof opposite to said atomizer head, said enlarged portion being of greater diameter than the diameter of said seals to provide a shoulder of larger diameter than the opening into which said seals fit, said atomizer head being proportioned to pass through an opening the diameter of said seals.

CERTIFICATE OF CORRECTION

Patent No. 2,878,067

March 17, 1959

James R. Grosholz

It is hereby certified that error appears in the printed specification of the above numbered patent requiring correction and that the said Letters Patent should read as corrected below.

Column 3, line 8, for "channels" read -- channel --; column 4, line 27, for "heat" read -- head --.

Signed and sealed this 7th day of July 1959.
